MINING MACHINE

William W. Sloane, Chicago, Ill., assignor to
Goodman Manufacturing Company, Chicago,
Ill., a corporation of Illinois

Application February 6, 1933, Serial No. 655,393
Renewed March 2, 1935

33 Claims. (Cl. 262—28)

This invention relates to improvements in mining machines and more particularly to mining machines of the type adapted to cut both horizontal and shearing kerfs in a mine wall.

5 The principal objects of my invention are to provide a new and improved mining machine of the class described constructed with a view towards utmost efficiency, adaptability for varying cutting conditions, ease, and safety of operation, 10 and so arranged as to provide a compact, mobile machine capable of cutting horizontal kerfs adjacent the mine floor or at various elevations with respect thereto and vertical or shearing kerfs without withdrawing the horizontal cutting element from the coal.

A prior application, Serial No. 488,439, filed October 13, 1930, shows a mining machine of the general type disclosed in my present application. My present application, however, relates 20 to certain novel improvements over the device shown in my prior application.

My invention may be more clearly understood with reference to the accompanying drawings wherein:

25 Figure 1 is a perspective view of one embodiment of my invention;

Figure 2 is a plan view of the device shown in Figure 1 with certain parts broken away and in section to more clearly show certain details 30 of my invention;

Figure 3 is an enlarged partial fragmentary end view showing certain details of the rearward portion of the cutting mechanism with parts broken away and in section and with the truck frame shown in vertical section;

Figure 4 is an enlarged top plan view of a portion of the embodiment of my invention illustrated in Figure 1, with parts broken away and in section to show certain details of the cutting mechanisms;

Figure 5 is an enlarged detail side elevation of a portion of the embodiment of my invention illustrated in Figure 1, with parts of the vertical shearing cutting mechanism shown in substantial longitudinal section;

Figure 6 is a sectional view taken substantially along line 6—6 of Figure 4;

Figure 7 is an enlarged detail view showing certain details of the means for selectively connecting the motor of one cutting mechanism to the other cutting mechanism;

Figure 8 is an enlarged detail forward end view of the shearing cutting mechanism with parts broken away and in section;

55 Figure 9 is an enlarged detail view of the for-

ward portion of the shearing cutting mechanism taken in side elevation showing certain details which are not shown in Figure 8;

Figure 10 is a sectional view taken substantially along line 10—10 of Figure 5;

Figure 11 is a sectional view taken substantially along line 11—11 of Figure 5;

Figure 12 is a sectional view taken substantially along line 12—12 of Figure 5; and

Figures 13, 14, and 15 are diagrammatic views showing the details of the mechanism for automatically controlling movement of the shearing cutting mechanism.

Like reference characters refer to like parts throughout the various figures.

The embodiment of my invention illustrated in the drawings, includes a truck 10 mounted on track wheels 11 and axles 12. Said truck is provided with a turntable 13, which turntable in turn supports a cutting element 14 disposed to one side of the center line of said turntable. Said cutting element is provided with a horizontal cutter bar 15 having a cutter chain 16 movable thereabout in a closed orbital path for cutting a horizontal kerf adjacent the mine bottom in front of and to each side of the mine track or at various elevations with respect thereto. An extensible and retractable shearing cutting element 17 including a cutter bar 18 having a cutter chain 19 movable thereabout in a closed orbital path in a vertical plane is also carried on said turntable on the opposite side thereof from the cutting element 14.

The cutting element 14 is of a type similar to that disclosed in a prior application of William T. McCullough, Serial No. 402,505, filed October 25, 1929, which issued as Patent No. 1,938,850 on December 12, 1933, so will not herein be shown or described in detail excepting to set forth certain parts necessary to clearly understand the invention and illustrate certain novel features not shown in said aforementioned prior application and includes a rearwardly disposed motor 20 having a cutter frame 21 extending forwardly thereof beyond said turntable and truck.

The cutter bar 15 is carried by the cutter frame 21 forwardly of the turntable 13 for pivotal movement about a vertical axis to permit adjustment of said cutter bar for cutting to each side of and in front of the track along the mine bottom, and for adjustment towards and away from said cutter frame in a plurality of parallel spaced guides 23 permitting adjustment of said cutter bar for cutting in a plurality of parallel planes in a manner fully disclosed in the aforementioned McCul-

lough application, so not herein described in detail. Likewise, suitable locking means (not shown in detail) are provided for locking said cutter bar in any desired angular position of adjustment with respect to said cutter frame.

The cutter frame 21 and cutting element 14 is supported on the turntable 13 rearwardly of the parallel spaced guides 23 for pivotal movement about an axis disposed transversely of said cutter frame on suitable trunnion supports, generally indicated by reference character 29, and movement of said cutting element about its axis of pivotal connection to said trunnion supports is controlled by a suitable yieldable adjusting means 15 in a usual manner and generally indicated by reference character 30.

The turntable 13 is herein preferably shown as being turned by a motor 31 mounted on the truck 10 rearwardly of said turntable and the cutting elements 14 and 17. A suitable system of reduction gears is provided for turning said turntable in a manner which has been fully described in my aforementioned prior application, and said turntable provides a means for adjusting the cutting position of the cutter bar 15 and feeding it across the face of the coal.

The apparatus is propelled about the mine and the cutter bar 15 may be fed into the coal or along the coal face by the track wheels 11 driven from the motor 31 through a suitable system of reduction gearing and suitable chain and sprocket drives in a manner which has been fully described in my aforementioned prior application, it being understood that flexible feeding means (not shown) may also be provided for sumping said cutter bar into or feeding said cutter bar along the coal face when desired.

Referring now in particular to the details of several of the novel features of my invention, the shearing cutting element 17 comprises a housing and support frame 33 split in a vertical plane and divided into a forward and rearward section. Said housing and support frame forms a bearing support for the cutter bar 18 and carries said cutter bar for pivotal movement about a horizontal axis extending transversely thereof in a manner which will hereinafter be more fully described and forms a housing and bearing support means for the gearing for pivoting said cutter bar and feeding it into or withdrawing it from the coal face. Said housing and support frame is supported by a guide frame 34 for slidable movement therealong. Said guide frame is secured to the turntable 13 in a suitable manner and extends parallel with and longitudinally of the cutting element 14 beyond the forward and rearward extremities of said turntable.

The guide frame 34 includes an angle 36 resting on suitable pads 32, 32 and secured to the turntable 13 on one of its legs, said leg extending towards the cutting element 14 and longitudinally of said cutting element. Said angle extends forwardly beyond the turntable and truck a substantial distance and rearwardly beyond said turntable. An angle 37 is secured to the vertical leg of the angle 36 adjacent the outer side thereof and its opposite leg extends inwardly toward the cutting element 14 in the same direction as the horizontal leg of the angle 36. The top face of the horizontal leg of the angle 37 is finished to form a slidable support for the housing and support frame 33. An upstanding support bracket 38 is secured to the forward portion of the angles 36 and 37 in a suitable manner and has a portion 75 extending inwardly and beneath a spacer plate

35 abutting the underside of the horizontal leg of the angle 36 and an upstanding portion extending along and secured to the outer sides of the vertical leg of the angle 37.

A T shaped guide member 39 is connected to a forked upper end of the support bracket 38 in a suitable manner. Said guide member extends rearwardly from the support bracket 38 and is secured to the forward side of a gear housing 40. Said gear housing extends upwardly from and is secured to a suitable bracket 46 extending rearwardly from the turntable 13 and to the rearward end of the angles 36 and 37 of the guide frame 34 in a suitable manner. The stem of the T shaped guide member 39 is adapted to engage a suitable guide groove 41 formed in the upper portion of the housing and support frame 33 for guiding the cutting element 17 for movement along the guide frame 34 and holding said support frame and the cutter bar 18 in a substantially vertical position. Suitable bearing shoes 42 and 43 are disposed adjacent the forward and rearward ends of the housing and support frame 33 and are adapted to rest on and have sliding engagement with the top surface of the angle 37. A suitable retaining member 44 is secured to the housing and support frame 33 beneath the bearing shoe 42 and has slidable engagement with a finished undersurface of the horizontal leg of the angle 37. A retaining member 45 is secured to the inner side of the housing and support frame 33 adjacent the bearing shoe 43 and has a portion adapted to engage a finished undersurface of the horizontal leg of the angle 37.

The cutter bar 18 is secured to a cutter bar support member 47, which cutter bar support member is provided with a circular groove disposed in a vertical plane and is adapted to be engaged with a suitable bearing member formed integral with the forward and rearward halves of the housing and support frame 33 so that said cutter bar support member may be pivotally moved about an axis extending transversely of the cutting element 17 to permit vertical feeding movement of said cutter bar.

A transversely extending shaft 48 is journaled within the cutter bar support member 47 in a suitable manner for rotation about an axis coaxial with the axis of pivotal movement of said cutter bar support member and has a sprocket 49 keyed to its outer end adjacent the cutting element 14 and a bevel gear 50 keyed to its inner end. Said sprocket meshes with and drives the cutter chain 19 about the cutter bar 18 in a usual manner and said bevel gear is driven from the motor 20 in a manner which will hereinafter be more fully described.

Referring now in particular to the means for driving the bevel gear 50 from the motor 20 and to the means for pivotally moving the cutter bar 18 about a transverse axis and for extending and retracting said cutter bar with respect to the truck 10, a splined shaft 51 is provided. Said splined shaft is journaled adjacent its forward end in a suitable ball-bearing 53 supported in the support bracket 38 in a usual manner. The rearward end of said splined shaft is carried in an internally splined hub of a spider 54 which carries a spur gear 55. The outer periphery of the hub of the spider 54 is journaled in a suitable bearing support, generally indicated by reference character 56, and carried by the gear housing 40 in the forward side thereof. The spur gear 55 is meshed with and driven by a reach gear 57 carried by the forward half of the gear housing 75.

40 on a suitable shaft secured thereto. Said reach gear in turn is meshed with and driven by a spur pinion 58 on the forward end of a longitudinally extending shaft 59 journaled in a suitable bearing support member 60 in a usual manner, which bearing support member is carried in the forward portion of the gear housing 40 and extends forwardly therefrom.

10 The forward end of the longitudinally extending shaft 59 is connected to a forwardly extending shaft 61 by means of a suitable universal connection in a usual manner and generally indicated by reference character 63. The forward end of the shaft 61 is splined and engages a splined sleeve 64, which sleeve in turn forms a portion of a universal connection generally indicated by reference character 65.

20 The universal connection 65 is adapted to have selective connection with the rearward end of a shaft 66 for the motor 20 through suitable clutch means which include a clutch member 67 having forwardly facing clutch jaws 68 formed integral therewith freely mounted on the motor shaft 66. Said clutch jaws are adapted to engage suitable clutch jaws 69 formed in the forward face of a member 70 keyed on the motor shaft 66 for driving the shaft 59 and spur pinion 58 from the motor 20 through the clutch member 67 and universal connections 63 and 65 in an obvious manner. A suitable nut 71 is provided on the rearward end of said motor shaft and is adapted to engage a suitable recessed portion in the clutch member 67 to limit rearward movement of said clutch member along said shaft.

30 35 The clutch member 67 is shifted along the shaft 66 by means of a suitable clutch collar 72 engageable with a groove formed around said clutch member and a clutch fork 73 engaging said collar in a usual manner. Said clutch fork is pivotally mounted on a rearwardly extending portion of the cutting element 14 on a pivotal pin 74. Said clutch fork is operated by a suitable hand lever 75 secured to the upper end of the pin 74.

45 50 The clutch member 67 is interlocked with the means for driving the cutter chain 16 about the horizontal cutter bar 15 in such a manner that the cutting elements 14 and 17 may not both be driven at the same time. This interlocking means is herein preferably shown as comprising a locking lever 76 secured to the pivotal pin 74 beneath the hand lever 75 and extending therefrom in a forwardly direction (see Figs. 2 and 4) and adapted to be engaged by or engage another locking lever 77 secured to a pivotal pin 78 pivotally supported in the frame for the cutting element 14 and spaced inwardly from the locking lever 76. When the locking lever 77 is held from movement and engages the locking lever 76, the hand lever 75 is locked in a fixed position in an obvious manner.

55 60 A lever arm 79 is secured to the pivotal pin 78 and extends inwardly therefrom and its outer end is connected to a connecting rod 80. The opposite end of said connecting rod has pivotal connection with a lever arm 81 secured to a pivotal pin 82. The pivotal pin 82 is journaled in the cutter frame 21 and has a clutch fork 83 secured thereto for operating said clutch fork and slidably moving a clutch member 84 along a sleeve 85 journaled in the cutter frame 21 and mounted on a longitudinally extending shaft 86 for free rotation with respect thereto. The sleeve 85 is driven from the forward end of the motor shaft 66 through a suitable gear reduction, generally

65 indicated by reference character 87. The clutch member 84 is feathered on the sleeve 85 and the shaft 86 is driven from said sleeve through a pinion 88 keyed to said shaft adapted to be engaged with teeth formed internally of the clutch member 84. The shaft 86 serves as a drive shaft for driving the cutter chain 16 about the cutter bar 15 and also as a means for adjusting the elevation of said cutter bar with respect to the mine bottom in a manner fully described in the aforementioned McCullough application. The pivotal pin 82 has a hand lever 89 secured to the upper end thereof for shifting the clutch member 84 along the sleeve 85 and shaft 86 for selectively connecting said shaft to the motor 20.

70 75 When the clutch jaws 68 are engaged with the clutch jaws 69, as shown in Figure 4, the locking lever 76 engages the locking lever 77 and holds said lever from pivotal movement in one direction, which in turn locks the hand lever 89 against movement and prevents engagement of the clutch member 84 with the pinion 88, and when the clutch jaws 68 are disengaged from the clutch jaws 69, the hand lever 89 is free to be moved for engaging the clutch member 84 with the pinion 88. Also, when the clutch member 84 is engaged with the pinion 88, the locking lever 77 engages the locking lever 76 and locks the hand lever 75 against movement.

80 85 The bevel gear 50 is driven from the splined shaft 51 through a bevel pinion 90 keyed on a sleeve member 91, which sleeve member in turn is journaled on a sleeve member 93 secured within an end plate 94 secured to the rearward end of the housing and support frame 33 by means of suitable nuts and bolts. The sleeve member 93 has a flange 95 abutting the inner side of the end plate 94 and the rearward end of the sleeve member 91, and its outer end has a collar 96 threaded thereon abutting the opposite side of the end plate 94 for holding said sleeve member in a stationary position. Likewise, the sleeve member 91 has an inwardly extending flange formed integral therewith which abuts the inner end of the sleeve member 93. Suitable clutch jaws 99 are formed integral with the forward end of the sleeve member 91 and are adapted to engage corresponding clutch jaws formed in a member 100. The member 100 is likewise provided with clutch jaws 101 which are adapted to be engaged by corresponding clutch jaws formed integral with a sleeve member 102 splined on the splined shaft 51. The forward end of the sleeve member 102 is adapted to abut a suitable bracket encircling the splined shaft 51 and formed integral with the housing and support frame 33. The member 100 is so arranged with respect to the sleeve 102 as to permit axial movement of said sleeve with respect to said member and the sleeve member 91 to compensate for flexing of the splined shaft 51 and permit the sleeve member 91 to be driven from said shaft without binding or heating of the driving parts.

90 95 Referring now in particular to the means for pivoting the cutter bar 18 and reciprocably moving said cutter bar along the guide frame 34, a spur gear 103 is cut integral with the sleeve member 91 and meshes with and drives a spur gear 104 disposed above said spur gear, a spur pinion 105 disposed to one side of said spur gear, and a spur gear 107 disposed beneath said spur gear.

100 105 The spur gear 104 is freely mounted on its hub in a suitable bearing member carried on a longitudinally extending shaft 108. Clutch sleeves 109, 109 abut each other and are keyed to the 75

longitudinally extending shaft 108. One of the clutch sleeves 109 forms one element of a friction disk clutch, generally indicated by reference character 110. Said friction disk clutch has connection with the spur gear 107 for selectively connecting said spur gear with the longitudinally extending shaft 108 in a usual manner.

The spur pinion 105 is secured to one end of a longitudinally extending shaft 111 in a suitable manner. Said shaft in turn is journaled intermediate its ends in suitable bearing support means secured to the housing and support frame 33 in a suitable manner. A spur gear 112 is secured to the opposite end of said longitudinally extending shaft and meshes with and drives spur gears 113 and 114 coaxial with the spur gears 104 and 107, respectively. The spur gear 113 is freely mounted on a suitable bearing member carried by the longitudinally extending shaft 108. The opposite clutch sleeve 109 from the spur gear 104 forms an element of a friction disk clutch, generally indicated by reference character 115, so that said clutch sleeve and the longitudinally extending shaft 108 may be driven from the spur gear 113 through said friction disk clutch in an opposite direction to which they are driven from the friction disk clutch 110. Thus, the longitudinally extending shaft 108 may be driven in opposite directions without reversal of the motor 20.

A sun gear 116 is keyed to the longitudinally extending shaft 108 forwardly of the hub of the spur gear 113 and meshes with and drives planetary pinions 117, 117 carried in a cage 118. Said planetary pinions mesh with an internal gear 119 keyed within a suitable support member formed integral with the housing and support frame 33 so that rotation of said longitudinally extending shaft will cause rotation of the cage 118 at a reduced speed. Said cage is journaled on its hub within a suitable bearing support member formed integral with the housing and support frame 33 and has driving connection with the rearward end of a longitudinally extending worm shaft 120 coaxial with the longitudinally extending shaft 108 and journaled at its rearward end on the forward end of said longitudinally extending shaft. The forward end of the longitudinally extending worm shaft 120 is journaled in a suitable bearing support formed integral with the housing and support frame 33.

A worm 121 is cut integral with the worm shaft 120 and meshes with and drives a worm gear 123 keyed on a transversely extending shaft 124, which shaft in turn is journaled in suitable bearing supports formed integral with the housing and support frame 33. The worm 121 and worm gear 123 are of the self-locking type; that is, the pitch of said worm and worm gear is such that said worm gear cannot drive said worm and will always be locked in a fixed position when not being driven by said worm. A pinion 125, herein preferably shown as being cut integral with the inner end of the transversely extending shaft 124, is provided which meshes with an arcuate rack 126. Said arcuate rack is secured to the cutter bar support member 47 and extends in a generally vertical plane so that rotation of the pinion 125 will pivotally move the cutter bar 18 to about the axis of pivotal movement of said cutter bar support member and the shaft 48.

Thus, the cutter bar 18 may be pivoted about an axis extending transversely of the shearing cutting element 17 at a relatively low frictionally controlled speed in reverse directions without re-

versal of the motor 20 for vertically adjusting or feeding said cutter bar, and said cutter bar may be locked in its various positions of angular adjustment with respect to the truck by means of the self-locking worm 121 and worm gear 123.

The spur gear 107 is freely mounted on a suitable bearing member carried on a longitudinally extending shaft 127 journaled at its rearward end in a suitable bearing support formed integral with the housing and support frame 33 and having a splined forward end engaging a splined bore of a worm shaft 129 journaled at its ends in a suitable bearing support means formed integral with the housing and support frame 33. Clutch sleeves 130, 130 are keyed to the longitudinally extending shaft 127. One of the clutch sleeves 130 has clutch means associated therewith forming a part of a friction disk clutch, generally indicated by reference character 131, for selectively driving the longitudinally extending shaft 108 from the spur gear 107 in one direction.

The spur gear 114 is freely mounted on a suitable bearing member carried on the longitudinally extending shaft 127. A friction disk clutch, generally indicated by reference character 134, is associated with the spur gear 114 and the clutch sleeve 130 opposite the spur gear 107 in such a manner that the longitudinally extending shaft 127 may be selectively driven by said spur gear in an opposite direction than from the spur gear 107.

A worm 135 is formed integral with the worm shaft 129 and meshes with and drives a worm gear 136 keyed on a transversely extending shaft 137 adjacent the inner end thereof. The pitch of the worm 135 and worm gear 136 is such that said worm gear will be locked in a fixed position when not being driven by said worm. A pinion 139 is keyed on the transversely extending shaft 137 adjacent the outer end thereof and meshes with and drives a spur gear 140 keyed on a transversely extending shaft 141 adjacent the outer end thereof. A rack pinion 143 is keyed on the opposite end of the transversely extending shaft 141 and meshes with a rack 144 secured to the outer side of the angle 37 in a suitable manner and extending longitudinally of the guide frame 34.

It is thus apparent that when the friction disk clutch 131 is in an engaged position, that the cutting element 17 will be moved along the guide frame 34 at a relatively low frictionally controlled speed, that when the friction disk clutch 134 is in an engaged position, said cutting element will be moved along the guide frame 34 in a reverse direction at a relatively low frictionally controlled speed without reversal of the direction of rotation of the motor 20, and that said cutting element may be locked in various fixed positions along said guide frame by means of the self-locking worm 135 and worm gear 136.

With reference now to the novel means for shifting the friction disk clutches 110, 115, 131, and 134, and automatically stopping pivotal or longitudinal movement of the cutter bar 18 which is best shown in Figures 10 to 15, inclusive, a common clutch collar 145 is arranged coaxial with the clutch sleeves 109, 109 for actuating the clutches 110 and 115 so that the clutch 110 will be in an engaged position when the clutch 115 is disengaged and vice versa. A clutch yoke 146 has engagement with the clutch collar 145. A clutch fork 147 is pivotally mounted on a rock shaft 148 extending transversely of the cutting element 17 and has operative engagement with 75

the clutch yoke 146. A hand lever 149 is keyed to the outer end of the rock shaft 148 so that movement of said hand lever will rock said shaft and engage the friction disk clutch 110 and dis-
5 engage the friction disk clutch 115 or vice versa.

Means are provided for automatically operating the clutch fork 147 and stopping pivotal movement of the cutter bar 18 when in an extreme up or down position which, as herein shown, 10 comprise a lever arm 150 secured to the rock shaft 148 and extending generally forwardly therefrom. A connecting link 151 is pivotally connected to the free end of the lever arm 150 and depends therefrom. The opposite end of said connect-
15 ing link is slotted and said slotted portion is adapted to receive a pin 153 extending inwardly from a lever arm 154 secured to a rock shaft 155 pivotally supported in the housing and support frame 33 (see Figs. 13, 14, and 15). Another 20 lever arm 156 extends forwardly and upwardly of the rock shaft 155. Said lever arm has an upper face of an arcuate shape and is adapted to be engaged by one arm 157 of an operating member 158 pivotally carried by the housing and support frame 33 for movement about a horizontal axis disposed intermediate its ends. An arm 159 extends forwardly of the arm 157 and is adapted to be engaged by a stop 160 on the cutter bar support member 47.

30 As is herein preferably shown, the friction disk clutch 115 is in an engaged position when it is desired that the cutter bar 18 be moved in an upwardly direction. Thus, when said cutter bar is moving in an upwardly direction and reaches the limits of its upward travel, the stop 160 will engage the arm 159 of the operating member 158. Further movement of said cutter bar in the same direction will pivotally move the operating member 158 and cause the arm 157 35 to pivot the lever arms 156 and 154 about the axis of the rock shaft 155, which in turn will move the connecting link 151 in an upwardly direction and pivotally move the lever arm 150 and rock shaft 148 in a counterclockwise direction for disengaging the friction disk clutch 115 and shifting the clutch collar 145 to a neutral position (see Fig. 14).

Referring now to Figure 15 and the means for automatically stopping downward movement of the cutter bar 18, a lever arm 161 is secured to the rock shaft 155 and depends therefrom. Said lever arm has a beveled lower face which is adapted to be engaged by an upwardly extending arm 162 of an operating member 163. Said operating member is carried on a pivotal pin 164, which pivotal pin is carried adjacent the forward portion of a member 165 disposed beneath the lever arm 161 and pivotally connected to the housing and support frame 33. Downward movement of the member 165 is limited by means of a stop 187. The operating member 163 is provided with a forwardly extending arm 166 which is adapted to be engaged by the stop 160 for pivotally moving said arm in a clockwise direction and in turn moving the lever arm 154 in a counterclockwise direction for disengaging the friction disk clutch 110 and shifting the clutch collar 145 to a neutral position, as shown in Figure 13.

It is thus apparent that automatic means have 70 been provided for automatically shifting the friction disk clutches 110 or 115 to a neutral position when the cutter bar 18 is in an extreme lowered or elevated position, said cutter bar being held in said positions by means of the worm 121 and worm gear 123 which are of the self-locking type,

and that this automatic shifting means is of a simplified construction and operates in a positive and efficient manner.

The clutches 131 and 134 are shifted by means of a suitable clutch fork 167 in a usual manner. The clutch fork 167 is carried on a vertically extending shaft 168. A lever arm 169 is formed integral with the clutch fork 167 and extends rearwardly therefrom in a direction towards the outer side of the cutting element 17. A lever arm 170 is pivotally connected to the outer end of the lever arm 169 and is keyed to a vertically extending rock shaft 171. The vertically extending rock shaft 171 is journaled in the rearward portion of the housing and support frame 33 and a hand lever 173 is keyed to its upper end so that pivotal movement of said hand lever will cause pivotal movement of the clutch fork 167 about the axis of the rock shaft 168 for shifting one or the other clutches 131 or 134. A lever arm 174 is keyed to 20 the lower end of the rock shaft 171 and extends inwardly therefrom. The lever arm 174 is adapted to be engaged by a suitable stop 175 extending forwardly of the gear housing 49 for moving said lever arm about the axis of pivotal movement of 25 the rock shaft 171 and shifting the friction disk clutch 134 to a neutral position and stopping rearward movement of the cutting element 17 along the guide frame 34.

A rod 176 is carried in the housing and support frame 33 adjacent the lower portion thereof for longitudinal slidable movement with respect thereto and its rearward end is in alignment with the free end of the lever arm 174. The forward end of the rod 176 is adapted to engage the sup- 35 port bracket 38 when the cutting element 17 is moving forwardly along the guide frame 34 for pivotally moving the lever arm 174 and shifting the friction disk clutch 131 to a neutral position when the cutting element 17 is in an extreme for- 40 ward position with respect to the guide frame 34.

Suitable interlocking means are provided for interlocking the clutches 110 and 134 and stopping rearward movement of the cutting element 17 along the guide frame 34 when the cutter bar 45 18 is in a downward position to prevent the cutter chain 19 from cutting into the truck 10 and turntable 13 and limiting downward movement of said cutter bar when the cutting element 17 is in a retracted position on said guide frame, which 50 means, as herein shown, comprise a lever arm 177 formed integral with the clutch fork 167 and extending outwardly and forwardly therefrom. A connecting link 178 has a slotted rearward end which has pivotal connection with a forked outer 55 end of the lever arm 177. Said connecting link in turn has a slotted forward end which has sidable engagement with a pivotal pin 179 secured to the lower end of a lever arm 180, which lever arm is in turn secured to the rock shaft 155. 60

A rider arm 183 extends downwardly from the member 165 and has a roller 184 carried adjacent its lower end, which roller is adapted to ride along a cam member 185. Said cam member extends longitudinally of the angle 36 for a portion of its 65 length and is secured to the upper face of the horizontal leg of the angle 36. The forward end of the cam member 185 is beveled to elevate the roller 184 and pivotally move the member 165 about its axis of pivotal connection to the hous- 70 ing and support frame 33 for elevating said member and the operating member 163 upon rearward movement of the shearing cutting element 17 along the guide frame 34. When the cutter bar 18 is positioned so that the cutter chain is liable 75

to cut into the truck and turntable upon rearward movement of the cutting element 17, the stop 160 will engage the arm 166 of the operating member 163 and hold the arm 162 in a relatively vertical position in engagement with the lever arm 161. As said cutting element moves rearwardly along the guide frame 34 and the roller 184 engages the beveled forward end of the cam member 185, the member 165 will be elevated which will pivot the operating member 163 about the center of pivotal movement of the pivotal pin 164 and move the arm 162 in a forwardly direction. This will in turn pivotally move the lever arm 161 about the axis of the rock shaft 155 and pivotally move the lever arm 180 in a counterclockwise direction. Movement of the lever arm 180 in a counterclockwise direction will cause movement of the connecting link 178 which in turn will pivot the lever arm 177 and throw the friction disk clutch 131 to a neutral position.

When the friction clutches 110 and 131 are both in an engaged position and the roller 184 engages the beveled forward end of the cam members 185, the lever arm 161 will actuate the lever arm 154 and throw the clutch 110 to a neutral position, as well as the clutch 131, in a manner which has hereinbefore been fully described. It should be understood that the slots in opposite ends of the connecting link 178 are so arranged as to prevent actuation of the lever arm 177 by means of the cam member 185 and roller 184 except when the cutter bar 18 is in a lowered position and to prevent actuation of the clutches 110 or 115 when either of the clutches 131 or 134 are operated.

It should be noted that the cam member 185 is gradually inclined upwardly towards the rearward end thereof to form a means for raising the pivotal axis of the operating member 166 as the cutting element 17 moves rearwardly along the guide frame 34 and thus change the position of engagement of the stop 160 with said operating member to permit said stop to engage said operating member in such a manner as to automatically stop downward pivotal movement of the cutter bar 18 and prevent the cutter chain 19 from cutting into the turntable 13 when said cutter bar is in various retracted positions with respect to the guide frame 34, and thus permit said cutter bar to swing in a greater arc when in an extended position with respect to said guide frame than when in a retracted position with respect to said guide frame.

It may thus be seen that a new and improved mining machine of a novel construction has been provided which may cut shearing kerfs in the mine wall when the horizontal cutter bar is dumped into the coal, which machine is so arranged that vertical pivotal movement of the shearing cutter bar is automatically controllable so as to be stopped in the desired position to minimize the possibility of breakage of the parts of the machine and digging into the mine wall or mine roof by the cutter bar, that reciprocable movement of said cutter bar along its guide frame is also automatically controllable so the cutting element may automatically be stopped when at either extreme end of its path of travel along the guide frame 34 and that the mechanisms for automatically shifting the clutches for controlling vertical and horizontal movement of the cutter bar are interconnected so as to prevent rearward horizontal movement of the cutting element beyond a certain predetermined point when the cutter bar 18 is in a lowered position.

It may also be seen that the shearing cutting

element is driven from the motor for operating a horizontal cutting element in a novel manner by a simplified system of gearing and that a novel mechanical interlocking means is provided to prevent operation of the shearing cutting element when the horizontal cutting element is in operation and vice versa.

Although I have herein shown and described one embodiment of my invention, it will be understood that the construction and arrangement of the various parts may be altered or changed without departing from the spirit or scope of my invention. Furthermore, I do not wish to be construed as limiting myself to the specific form illustrated herein, excepting as it may be particularly limited in the appended claims.

I claim as my invention:

1. In a mining machine, a frame, a kerf cutter thereon, means for pivotally moving said kerf cutter about an axis disposed adjacent one of its ends, means for extending or retracting said kerf cutter with respect to said frame, automatic means for stopping pivotal movement of said kerf cutter when in one extreme position or another and other automatic means interconnected with said first-mentioned automatic means for stopping retraction of said kerf cutter when said kerf cutter is in a lowered position with respect to said frame.

2. In a mining machine, a frame, a kerf cutter thereon, means for pivotally moving said kerf cutter about an axis disposed adjacent one of its ends, power driven means for swinging said kerf cutter in a vertical plane, power driven means for extending and retracting said kerf cutter with respect to said frame, and automatic means interconnected between said means for pivoting said kerf cutter in a vertical plane and said means for extending or retracting said kerf cutter, for stopping retraction of said kerf cutter when said kerf cutter is in a lowered position with respect to said frame.

3. In a mining machine, a frame, a kerf cutter thereon, means for extending or retracting said kerf cutter with respect to said frame, means for swinging said kerf cutter in a vertical plane, automatic means for stopping extension or retraction of said kerf cutter when in one extreme position or another, and other automatic means for stopping retraction of said kerf cutter when said kerf cutter is in a lowered position with respect to said frame.

4. In a mining machine, a frame, a kerf cutter thereon, means for extending or retracting said kerf cutter with respect to said frame, means for swinging said kerf cutter in a vertical plane, automatic means for stopping extension or retraction of said kerf cutter when in one extreme position or another, and other automatic means interconnected with said means for stopping extension or retraction of said kerf cutter for stopping retraction of said kerf cutter when said kerf cutter is in a lowered position with respect to said frame.

5. In a mining machine, a frame, a kerf cutter thereon, means for extending or retracting said kerf cutter with respect to said frame, means for swinging said kerf cutter in a vertical plane, automatic means for stopping extension or retraction of said kerf cutter when in one extreme position or another, automatic means for stopping pivotal movement of said kerf cutter when in one extreme position or another, and other automatic means, connectible with said means for automatically stopping extension or retrac-

- tion of said kerf cutter when in one extreme position or another, for stopping retraction of said kerf cutter when said kerf cutter is in a lowered position with respect to said frame.
- 5 6. In a mining machine, a frame, a kerf cutter thereon, means for extending or retracting said kerf cutter with respect to said frame, means for swinging said kerf cutter in a vertical plane, automatic means for stopping extension or retraction of said kerf cutter when in one extreme position or another, automatic means for stopping swinging movement of said kerf cutter when in one extreme position or another, and other automatic means, interconnected between said 10 means for stopping extension and retraction of said cutter bar when in one extreme position or another and said means for stopping swinging movement of said cutter bar when in one extreme position or another, for stopping swinging movement of said cutter bar in a downwardly direction when said cutter bar is in a retracted position with respect to said frame.
- 15 7. In a mining machine, a frame, a kerf cutter thereon, means for pivotally moving said kerf cutter about an axis disposed adjacent one of its ends, means for extending or retracting said kerf cutter with respect to said frame, automatic means for stopping swinging movement of said kerf cutter when at one extreme position or another and for stopping extension or retraction of said kerf cutter along said frame when in one extreme position or another, and means interconnected with said means for automatically stopping extension or retraction of said kerf cutter along said frame for automatically stopping downward swinging movement of said kerf cutter at a predetermined point when in a retracted position with respect to said frame.
- 20 8. In a mining machine, a frame, a kerf cutter thereon comprising a cutter bar having a cutter chain movable thereabout, a motor, a geared connection from said motor to said cutter bar for driving said cutter chain about said cutter bar and for pivotally moving said cutter bar about an axis disposed adjacent its rearward end in reverse directions without reversal of said motor, another geared connection from said motor to said cutter bar for moving said cutter bar along said frame in reverse directions without reversal of said motor, and means for automatically stopping pivotal movement of said cutter bar when in one extreme position or another comprising clutch mechanism in said geared connection from said motor to said cutter bar, and mechanism connectible with said clutch mechanism and cutter bar for automatically shifting said clutch mechanism.
- 25 9. In a mining machine, a frame, a kerf cutter thereon including a cutter bar movable about a horizontal axis, means for pivotally moving said cutter bar comprising a motor, a shaft driven thereby, a parallel shaft, a plurality of clutches on said parallel shaft, geared connections between said shafts for driving said second-mentioned shaft in one direction when one of said clutches is connected thereto and in an opposite direction when said opposite clutch is connected thereto, a geared connection from said last-mentioned shaft to said cutter bar, manually operated mechanism for shifting said clutches for connecting one or the other of said clutches to said shaft, and automatic means for shifting said clutches to a neutral position when said cutter bar is in one extreme position or another comprising a stop movable with said cutter bar and
- 30 engageable with the mechanism for shifting said clutches.
- 35 10. In a mining machine, a frame, a kerf cutter thereon, means for extending or retracting said kerf cutter with respect to said frame, means for swinging said kerf cutter in a vertical plane, automatic means for stopping extension or retraction of said kerf cutter when in one extreme position or another, other automatic means for stopping swinging movement of said kerf cutter when in one extreme position or another and limiting downward swinging movement thereof when in a retracted position with respect to said frame and permitting the arc of swinging movement of said kerf cutter to increase as it is extended along said frame.
- 40 11. In a mining machine, a frame, a kerf cutter thereon, means for extending or retracting said kerf cutter with respect to said frame, means for swinging said kerf cutter in a vertical plane, automatic means for stopping extension or retraction of said kerf cutter when in one extreme position or another, other automatic means for stopping swinging movement of said kerf cutter when in one extreme position or another and limiting downward movement thereof when in a retracted position with respect to said frame and permitting the arc of swinging movement of said kerf cutter to increase as it is extended along said frame including a cam member extending longitudinally along said frame, said cam member being inclined upwardly towards the rearward end of said frame.
- 45 12. In a mining machine, a frame, a kerf cutter thereon, means for extending or retracting said kerf cutter with respect to said frame, means for swinging said kerf cutter in a vertical plane, automatic means for stopping extension or retraction of said kerf cutter when in one extreme position or another, other automatic means for stopping swinging movement of said kerf cutter when in one extreme position or another and limiting downward movement thereof when in a retracted position with respect to said frame and permitting the arc of swinging movement of said kerf cutter to increase as it is extended along said frame including a cam member inclined upwardly towards the rearward end of said frame and extending longitudinally therealong, and stopping mechanism movable along said cam.
- 50 13. In a mining machine, a frame, a kerf cutter thereon, means for pivotally moving said kerf cutter about an axis disposed adjacent one of its ends, means for extending or retracting said kerf cutter with respect to said frame, automatic means for stopping swinging movement of said kerf cutter when at one extreme position or another and other automatic means for stopping extension or retraction of said kerf cutter along said frame when in one extreme position or another, and means interconnected with said means for automatically stopping extension or retraction of said kerf cutter along said frame for automatically stopping downward swinging movement of said kerf cutter at a predetermined point when in a retracted position with respect to said frame and changing the position of this point as said kerf cutter is moved forwardly along said frame to permit the arc of movement of said kerf cutter to be increased as said kerf cutter is extended along said frame.
- 55 14. In a mining machine, a frame, a kerf cutter thereon, means for pivotally moving said kerf cutter about an axis disposed adjacent one of its ends, means for extending or retracting

10 said kerf cutter with respect to said frame, automatic means for stopping swinging movement of said kerf cutter when at one extreme position or another and other automatic means for stopping extension or retraction of said kerf cutter along said frame when in one extreme position or another, means interconnected with said means for automatically stopping extension or retraction of said kerf cutter along said frame for limiting downward swinging movement of said kerf cutter when in a retracted position with respect to said frame including a cam member on said frame, a rider member adapted to engage said cam member, and an operative connection 15 between said rider member and the means for controlling pivotal movement of said kerf cutter and the means for controlling extension or retraction of said kerf cutter with respect to said frame.

20 15. In a mining machine, a frame, a kerf cutter thereon, means for pivotally moving said cutter about an axis disposed adjacent one of its ends, means for extending or retracting said kerf cutter with respect to said frame, automatic
25 means for stopping pivotal movement of said kerf cutter when at one extreme position or another and other automatic means for stopping extension or retraction of said kerf cutter along said frame when in one extreme position or another, and means interconnected with said means
30 for automatically stopping extension or retraction of said kerf cutter along said frame for limiting downward pivotal movement of said kerf cutter when in a retracted position with respect
35 to said frame and permitting the arc of pivotal movement of said kerf cutter to increase as said kerf cutter is extended along said frame including a cam member extending longitudinally along said frame and being inclined upwardly towards
40 the rearward end thereof, a rider member adapted to engage and ride along said cam member, and operative connections between said rider member and the means for controlling pivotal movement of said kerf cutter and the means for
45 controlling extension or retraction of said kerf cutter with respect to said frame.

16. In a mining machine, a frame, a kerf cutter thereon including a cutter bar movable about a horizontal axis, means for pivotally moving
50 said cutter bar comprising a motor, a shaft driven thereby, a parallel shaft, a plurality of clutches on said parallel shaft, geared connections between said shafts for driving said second-mentioned shaft in one direction when one of said
55 clutches is connected thereto and in an opposite direction when said opposite clutch is connected thereto, a geared connection from said last-mentioned shaft to said cutter bar, manually operated means for shifting said clutches for connecting
60 one or the other of said clutches to said shaft, and automatic means for shifting said clutches to a neutral position when said cutter bar is in one extreme position or another comprising a stop movable with said cutter bar, a member disposed above the pivotal axis of said cutter bar having operative connection with said mechanism for shifting said clutches and adapted to be engaged by said stop and another member disposed beneath the pivotal axis of said cutter
65 bar adapted to be engaged by said stop and having operative connection with said mechanism for shifting said clutches.
70

17. In a mining machine, a frame, a kerf cutter thereon including a cutter bar movable about a horizontal axis, means for pivotally moving

said cutter bar comprising a motor, a shaft driven thereby, a parallel shaft, a plurality of clutches on said parallel shaft, geared connections between said shafts for driving said second-mentioned shaft in one direction when one of said clutches is connected thereto and in an opposite direction when said opposite clutch is connected thereto, a geared connection from said last-mentioned shaft to said cutter bar, manually operated means for shifting said clutches for connecting one or the other of said clutches to said shaft, and automatic means for shifting said clutches to a neutral position when said cutter bar is in one extreme position or another comprising a stop connectible with said cutter bar, 15 a member disposed above the pivotal axis of said cutter bar adapted to be engaged by said stop, another member disposed beneath the pivotal axis of said cutter bar adapted to be engaged by said stop, a member interposed between said members and adapted to be engaged by each of said members and an operative connection from said last-mentioned member to said clutches. 20

18. In a mining machine, a frame, a kerf cutter thereon including a cutter bar movable about a 25 horizontal axis and movable along said frame in reverse directions, means for pivotally moving said cutter bar comprising a motor, a shaft driven thereby, a parallel shaft, a plurality of clutches on said parallel shaft, geared connections between 30 said shafts for driving said second-mentioned shaft in one direction when one of said clutches is connected thereto and in an opposite direction when said opposite clutch is connected thereto, a geared connection from said last-mentioned shaft 35 to said cutter bar, manually operated means for shifting said clutches for connecting one or the other of said clutches to said shaft, another shaft parallel to said first-mentioned shaft and on the opposite side thereof from said second-mentioned shaft, a plurality of clutches on said third-mentioned shaft, geared connections between said first and third-mentioned shafts for driving said third-mentioned shaft from said first-mentioned shaft in one direction when one of said clutches 40 is connected thereto and in an opposite direction when said opposite clutch is connected thereto, a geared connection from said last-mentioned shaft to said frame for moving said kerf cutter along said frame, manually operated means for shifting said clutches, automatic means for shifting said clutches when said kerf cutter is at one end or the other of its path of travel, and means interconnected with said clutches for controlling pivotal movement of said cutter bar for stopping rearward movement of said kerf cutter along said frame when said cutter bar is in a lowered position comprising a lever arm having connection with said clutches for moving said kerf cutter along said frame, and means carried by said kerf cutter having operative connection with said lever arm and adapted to be engaged by said cutter bar for actuating said lever arm when said cutter bar is in a downward position.

19. In a mining machine, a frame, a kerf cutter thereon including a cutter bar movable about a horizontal axis and movable along said frame in reverse directions, means for pivotally moving said cutter bar comprising a motor, a shaft driven thereby, a parallel shaft, a plurality of clutches on said parallel shaft, geared connections between said shafts for driving said second-mentioned shaft in one direction when one of said clutches is connected thereto and in an opposite direction when said opposite clutch is connected thereto, a

geared connection from said last-mentioned shaft to said cutter bar, manually operated means for shifting said clutches for connecting one or the other of said clutches to said shaft, another shaft parallel to said first-mentioned shaft and on the opposite side thereof from said second-mentioned shaft, a plurality of clutches on said third-mentioned shaft, geared connections between said first and third-mentioned shafts for driving said third-mentioned shaft from said first-mentioned shaft in one direction when one of said clutches is connected thereto and in an opposite direction when said opposite clutch is connected thereto, a geared connection from said last-mentioned shaft to said frame for moving said kerf cutter along said frame, manually operated means for shifting said clutches, automatic means for shifting said clutches when said kerf cutter is at one end or the other of its path of travel, and means interconnected with said clutches for controlling pivotal movement of said cutter bar for stopping rearward movement of said kerf cutter along said frame when said cutter bar is in a lowered position comprising a lever arm having connection with said clutches for moving said kerf cutter along said frame, another lever arm movable with said first-mentioned lever arm having connection with said clutches for controlling pivotal movement of said cutter bar, and means carried by said kerf cutter having operative connection with said lever arms and adapted to be engaged by said cutter bar for actuating said lever arms when said cutter bar is in a downward position.

20. In a mining machine, a frame, a kerf cutter thereon including a cutter bar movable about a horizontal axis and movable along said frame in reverse directions, means for pivotally moving said cutter bar comprising a motor, a shaft driven thereby, a parallel shaft, a plurality of clutches on said parallel shaft, geared connections between said shafts for driving said second-mentioned shaft in one direction when one of said clutches is connected thereto and in an opposite direction when said opposite clutch is connected thereto, a geared connection from said last-mentioned shaft to said cutter bar, manually operated means for shifting said clutches for connecting one or the other of said clutches to said shaft, another shaft parallel to said first-mentioned shaft and on the opposite side thereof from said second-mentioned shaft, a plurality of clutches on said third-mentioned shaft, geared connections between said first and third-mentioned shafts for driving said third-mentioned shaft from said first-mentioned shaft in one direction when one of said clutches is connected thereto and in an opposite direction when said opposite clutch is connected thereto, a geared connection from said last-mentioned shaft to said frame for moving said kerf cutter along said frame, manually operated means for shifting said clutches, automatic means for shifting said clutches when said kerf cutter is at one end or the other of its path of travel, and means interconnected with said clutches for controlling pivotal movement of said cutter bar for stopping rearward movement of said kerf cutter along said frame when said cutter bar is in a lowered position comprising a lever arm having operative connection with said clutches for moving said kerf cutter along said frame, a stop connected with said cutter bar, and means carried by said kerf cutter having operative connection with said lever arm and adapted to be engaged by said stop when said cutter bar is in a lowered position for

actuating said lever arm when said kerf cutter is moved rearwardly along said frame.

21. In a mining machine, a frame, a kerf cutter thereon including a cutter bar movable about a horizontal axis and movable along said frame in reverse directions, means for pivotally moving said cutter bar comprising a motor, a shaft driven thereby, a parallel shaft, a plurality of clutches on said parallel shaft, geared connections between said shafts for driving said second-mentioned shaft in one direction when one of said clutches is connected thereto and in an opposite direction when said opposite clutch is connected thereto, a geared connection from said last-mentioned shaft to said cutter bar, manually operated means for shifting said clutches for connecting one or the other of said clutches to said shaft, another shaft parallel to said first-mentioned shaft and on the opposite side thereof from said second-mentioned shaft, a plurality of clutches on said third-mentioned shaft, geared connections between said first and third-mentioned shafts for driving said third-mentioned shaft from said first-mentioned shaft in one direction when one of said clutches is connected thereto and in an opposite direction when said opposite clutch is connected thereto, a geared connection from said last-mentioned shaft to said frame for moving said kerf cutter along said frame, manually operated means for shifting said clutches, automatic means for shifting said clutches when said kerf cutter is at one end or the other of its path of travel, and means interconnected with said clutches for controlling pivotal movement of said cutter bar for stopping rearward movement of said kerf cutter along said frame when said cutter bar is in a lowered position comprising a lever arm having connection with said clutches for moving said kerf cutter along said frame, another lever arm movable with said first-mentioned lever arm having connection with said clutches for controlling pivotal movement of said cutter bar, a stop connected with said cutter bar, and means carried by said kerf cutter having operative connection with said lever arms and adapted to be engaged by said stop when said cutter bar is in a lowered position for actuating said lever arms and shifting said clutches to a neutral position when said kerf cutter is moved rearwardly.

22. In a mining machine, a frame, a kerf cutter thereon including a cutter bar movable about a horizontal axis and movable along said frame in reverse directions, means for swinging said cutter bar in a vertical plane comprising a motor, a shaft driven thereby, a parallel shaft, a plurality of clutches on said parallel shaft, geared connections between said shafts for driving said second-mentioned shaft in one direction when one of said clutches is connected thereto and in an opposite direction when said opposite clutch is connected thereto, a geared connection from said last-mentioned shaft to said cutter bar, manually operated means for shifting said clutches for connecting one or the other of said clutches to said shaft, another shaft parallel to said first-mentioned shaft and on the opposite side thereof from said second-mentioned shaft, a plurality of clutches on said third-mentioned shaft, geared connections between said first and third-mentioned shafts for driving said third-mentioned shaft in one direction when one of said clutches is connected thereto and in an opposite direction when said opposite clutch is connected thereto.

- a geared connection from said last-mentioned shaft to said frame for moving said kerf cutter along said frame, manually operated means for shifting said clutches, automatic means for shifting said clutches when said kerf cutter is at one end or the other of its path of travel, and means interconnected with said clutches for controlling pivotal movement of said cutter bar for stopping rearward movement of said kerf cutter along said frame when said cutter bar is in a lowered position comprising a lever arm having connection with said clutches for moving said kerf cutter along said frame, a stop connected with said cutter bar, and means carried by said kerf cutter having operative connection with said lever arm and adapted to be engaged by said stop for actuating said lever arm when said kerf cutter is moved rearwardly along said frame and said cutter bar is in a lowered position comprising a cam on said frame, a member pivoted on said kerf cutter and having a roller thereon adapted to engage same cam and a member adapted to be engaged by said stop having pivotal connection with said member and having operative connection with said lever arm for operating said clutches.
23. In a mining machine, a frame, a kerf cutter thereon including a cutter bar movable about a horizontal axis and movable along said frame in reverse directions, means for pivotally moving said cutter bar comprising a motor, a shaft driven thereby, a parallel shaft, a plurality of clutches on said parallel shaft, geared connections between said shafts for driving said second-mentioned shaft in one direction when one of said clutches is connected thereto and in an opposite direction when said opposite clutch is connected thereto, a geared connection from said last-mentioned shaft to said cutter bar, manually operated means for shifting said clutches for connecting one or the other of said clutches to said shaft, another shaft parallel to said first-mentioned shaft and on the opposite side thereof from said second-mentioned shaft, a plurality of clutches on said third-mentioned shaft, geared connections between said first and third-mentioned shafts for driving said third-mentioned shaft from said first-mentioned shaft in one direction when one of said clutches is connected thereto and in an opposite direction when said opposite clutch is connected thereto, a geared connection from said last-mentioned shaft to said frame for moving said kerf cutter along said frame, manually operated means for shifting said clutches, automatic means for shifting said clutches when said kerf cutter is at one end or the other of its path of travel, and means interconnected with said clutches for controlling pivotal movement of said cutter bar for stopping rearward movement of said kerf cutter along said frame when said cutter bar is in a lowered position comprising a lever arm having connection with said clutches for moving said kerf cutter along said frame, another lever arm movable with said first-mentioned lever arm having connection with said clutches for controlling pivotal movement of said cutter bar, a stop connected with said cutter bar, and means carried by said kerf cutter having operative connection with said lever arms and adapted to be engaged by said stop when said cutter bar is in a lowered position for actuating said lever arms and shifting said clutches to a neutral position when said kerf cutter is moved rearwardly comprising a cam on said frame, a member pivoted on said kerf cutter and having a roller thereon adapted to engage

said cam and a member adapted to be engaged by said stop having pivotal connection with said member and having operative connection with said lever arm for operating said clutches.

24. In a mining machine, a frame, a kerf cutter thereon including a cutter bar movable about a horizontal transverse axis, a motor, a drive connection from said motor to said cutter bar for moving said cutter bar about said horizontal axis in reverse directions without reversal of said motor including a plurality of clutches, manually operated means for shifting said clutches, and automatic means for shifting said clutches to a neutral position when said cutter bar is in one extreme position or another comprising a stop movable with said cutter bar and engageable with the mechanism for shifting said clutches. 5

25. In a mining machine, a frame, a kerf cutter thereon including a cutter bar movable about a horizontal transverse axis, a motor, a drive connection from said motor to said cutter bar for moving said cutter bar about said horizontal transverse axis in reverse directions without reversal of said motor including a plurality of clutches, manually operated means for shifting 20 said clutches, and automatic means for shifting said clutches to a neutral position when said cutter bar is in one extreme position or another comprising a stop connectible with said cutter bar, a member disposed above the pivotal axis of 30 said cutter bar adapted to be engaged by said stop, another member disposed beneath the pivotal axis of said cutter bar adapted to be engaged by said stop, a member interposed between said members and adapted to be engaged by each of 35 said members, and an operative connection from said last-mentioned member to each of said clutches.

26. In a mining machine, a frame, a kerf cutter mounted thereon for reciprocable movement 40 with respect thereto including a cutter bar movable about a horizontal transverse axis, a motor, a drive connection from said motor to said kerf cutter for reciprocably moving said kerf cutter along said frame without reversal of said motor 45 including a plurality of clutches, manually operated means for shifting said clutches and automatic means for shifting said clutches when said kerf cutter is in extreme positions with respect to said frame, a drive connection from said motor to said cutter bar for moving said cutter bar about said horizontal transverse axis in reverse directions without reversal of said motor including a plurality of clutches, manually operated means for shifting said clutches, automatic means for 50 shifting said clutches when said cutter bar is in one extreme position or another, and means interconnected with said automatic means for shifting both sets of said clutches to neutral positions when said cutter bar is at either extreme of its 55 longitudinal or angular travel for stopping rearward movement of said kerf cutter along said frame when said cutter bar is in a lowered position comprising a stop connected with said cutter bar adapted to engage said automatic shifting 60 means when said cutter bar is in a lowered position, and means carried by said kerf cutter for actuating said automatic shifting means when said kerf cutter is moving in a rearward direction 65 along said frame. 70

27. In a mining machine, a frame, a kerf cutter mounted thereon for reciprocable movement with respect thereto including a cutter bar movable about a horizontal transverse axis, a motor, a drive connection from said motor to said kerf 75

cutter for reciprocably moving said kerf cutter along said frame without reversal of said motor including a plurality of clutches, manually operated means for shifting said clutches, and automatic means for shifting said clutches when said kerf cutter is in extreme positions with respect to said frame, a drive connection from said motor to said cutter bar for moving said cutter bar about said horizontal transverse axis in reverse directions without reversal of said motor including a plurality of clutches, manually operated means for shifting said clutches when said cutter bar is in one extreme position or another, and means interconnected with said automatic means for shifting both sets of said clutches to neutral positions when said cutter bar is at either extreme of its longitudinal or angular travel for stopping rearward movement of said kerf cutter along said frame when said cutter bar is in a lowered position comprising a stop connected with said cutter bar adapted to engage said automatic shifting means when said cutter bar is in a lowered position, and means carried by said kerf cutter for actuating said automatic shifting means when said cutter bar is in a lowered position and is moving in a rearward direction along said frame comprising a cam member on said frame and a rider member carried by said kerf cutter engageable with said cam member and having operative connection with said automatic shifting means.

28. In a mining machine, a support, and horizontal and shearing cutting mechanism thereon including a horizontally disposed kerf cutter on said support adapted to cut a horizontal kerf in the mine wall, and a vertically movable kerf cutter adapted to cut a shearing kerf in the mine wall carried on said support for extension and retraction with respect thereto, a motor on said support, a drive connection from said motor to said horizontal cutting mechanism, another drive connection from said motor to said vertical cutting mechanism, and interlocking means interposed between said drives to said cutting mechanisms to prevent the driving of one cutting mechanism while the other is in operation.

29. In a mining machine, a support, and horizontal and shearing cutting mechanism thereon including a horizontal cutter bar having a cutter chain movable thereabout, a motor on said support, a drive connection from said motor to said cutter chain, another cutter bar having a cutter chain movable thereabout carried by said support for extension and retraction with respect thereto and for swinging movement in a vertical plane for cutting a shearing kerf in the mine wall, a drive connection from said motor to said second cutter chain, and mechanical interlocking means interposed between said motor and the mechanisms for driving said cutter chains to prevent the driving of one cutter chain while the other cutter chain is in operation.

30. In a mining machine, a support, and horizontal and shearing cutting mechanism thereon including a horizontal cutter bar having a cutter chain movable thereabout, a motor on said support, a selective drive connection from said motor to said cutter chain including a clutch mechanism, another cutter bar having a cutter chain movable thereabout carried by said support for extension and retraction with respect thereto and for pivotal movement in a vertical plane for cutting a shearing kerf in the mine wall, a selective drive connection from said motor to said

second cutter chain including a clutch mechanism, manually operable means for shifting said clutch mechanism, and mechanical interlocking means for interlocking said shifting mechanisms to prevent the driving of one cutter chain while the other cutter chain is in operation comprising a lever arm connectible with one of said clutch shifting mechanisms, a locking arm connectible with said other clutch shifting mechanism, and a connection between said lever arm and locking arm.

31. In a mining machine, a support, and horizontal and shearing cutting mechanism thereon including a horizontal cutter bar having a cutter chain movable thereabout, a motor on said support, a selective drive connection from said motor to said cutter chain including a clutch mechanism, another cutter bar having a cutter chain movable thereabout carried by said support for extension and retraction with respect thereto and for swinging movement in a vertical plane for cutting a shearing kerf in the mine wall, a selective drive connection from said motor to said second cutter chain including a clutch mechanism, manually operable means for shifting said clutch mechanisms, and mechanical interlocking means for interlocking said shifting mechanisms to prevent the driving of one cutter chain while the other cutter chain is in operation comprising a lever arm connectible with one of said clutch shifting mechanisms, a locking arm connectible with said other clutch shifting mechanism, and a connection between said lever arm and locking arm comprising a pivotally movable member operatively connectible with said lever arm, and adapted to engage said locking arm.

32. In a mining machine, a support, and horizontal and shearing cutting mechanism thereon including a horizontal cutter bar having a cutter chain movable thereabout, a motor on said support, a drive connection from said motor to said cutter chain, another cutter bar having a cutter chain movable thereabout carried by said support for extension and retraction with respect thereto and for pivotal movement in a vertical plane for cutting a shearing kerf in the mine wall, a drive connection from said motor to said second-mentioned cutter chain for driving said cutter chain about said cutter bar, extending and retracting said second-mentioned cutter bar with respect to said support, and pivotally moving said cutter bar in a vertical plane, and mechanical interlocking means interposed between said motor and drive connections to prevent the driving of one cutter chain while the other cutter chain is in operation.

33. In a mining machine, a support, and horizontal and shearing cutting mechanism thereon including a horizontal cutter bar having a cutter chain movable thereabout, a motor on said support, a drive connection from said motor to said cutter chain, another cutter bar having a cutter chain movable thereabout carried by said support for extension and retraction with respect thereto and for pivotal movement in a vertical plane for cutting a shearing kerf in the mine wall, a drive connection from said motor to said second-mentioned cutter chain for driving said cutter chain about said cutter bar, extending and retracting said second-mentioned cutter bar with respect to said support, and pivotally moving said cutter bar in a vertical plane, mechanical interlocking means interposed between said motor and drive connections to prevent the driving of one cutter chain while the other cutter chain

is in operation and automatic means for stopping vertical or extensible and retractable movement of said shearing cutter bar when at either extremes of vertical movement or longitudinal travel with respect to said support comprising a separate clutch for controlling longitudinal and

vertical movement of said cutter bar and mechanism connectible with said clutch mechanism and engageable with said cutter bar and support for shifting said clutch mechanisms.
